L. TOPKIS,
UNDERGARMENT.
APPLICATION FILED SEPT. 25, 1915.

1,191,369.

Patented July 18, 1916.

UNITED STATES PATENT OFFICE.

LOUIS TOPKIS, OF WILMINGTON, DELAWARE.

UNDERGARMENT.

1,191,369.

Specification of Letters Patent. Patented July 18, 1916.

Application filed September 25, 1915. Serial No. 52,555.

To all whom it may concern:

Be it known that I, Louis Topkis, a citizen of the United States, residing at Wilmington, in the county of New Castle and State of Delaware, have invented certain new and useful Improvements in Undergarments, of which the following is a specification.

My invention relates to improvements in undergarments, the object of the invention being to provide an undergarment with an improved construction of ventilated crotch which is especially adapted for use in connection with union suits, drawers, or other similar garments, and which not only permits of a certain amount of elasticity, but also allows ventilation to render the garment comfortable to the wearer.

A further object is to provide an improved construction of crotch in which flexible woven material is employed in two thicknesses, which gives the necessary strength and durability, and provide in the double thickness of material sewed or embroidered eyelets which permit a free circulation of air through the crotch, and also operate as a connecting medium between the two thicknesses of material.

With these and other objects in view, the invention consists in certain novel features of construction and combinations and arrangements of parts as will be more fully hereinafter described and pointed out in the claims.

In the accompanying drawings: Figure 1 is a view in front elevation of an undergarment having my improved construction of crotch. Fig. 2 is a plan view of the crotch when flattened out, and Fig. 3 is a view in section on line 3—3 of Fig. 2.

1 represents the garment which may constitute a union suit as shown, and which is provided with legs 2, 2.

3 represents the improved crotch which is widest at its center, and tapers to both ends, and the material of the garment at the inner seams of the legs and body portion is cut out to receive and accommodate the crotch 3.

In constructing the crotch, I utilize a fabric which is capable of stretching, yet which embodies the necessary strength and durability, and in order to provide the necessary strength and wearing qualities at the intermediate portion of the crotch, I provide a reinforcing sheet 4 which is secured to the main portion of the crotch by elastic

stitching 5. These stitches are so made that they permit the goods to expand and contract without tearing the stitches, and they extend transversely of the crotch at the edges of the sheet 4 as shown clearly in Fig. 2. In the double thickness of material at the center of the crotch, I provide eyelets 6 which are of the type known as embroidered or stitched eyelets, the threads forming the eyelets extending through both thicknesses of material and operating to form the openings, and also to secure the two thicknesses of material together. The material of the crotch may, of course, be varied, but I use preferably what is known on the market as webbing, and the two thicknesses are so connected that the material can stretch in all directions, yet securely hold the several parts of the garment together, and provide a smooth ventilated crotch most efficiently performing the functions for which it is intended.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

1. A garment having leg portions with an opening adjacent the crotch thereof, a piece of flexible material fitting said opening and having its edges secured to the edges providing said opening, said piece having holes providing vents therein, a second piece of flexible material having opposite edges in alignment with and secured by stitching to opposite edges of said first piece, said second piece having two other edges which are secured by resilient stitches to said first piece, said second piece having holes in alignment with the holes of said first piece and forming vents, the edges forming the vents of each of said pieces being bound by stitching which passes through and secures both of said pieces together, substantially as described.

2. A garment having leg portions with an opening adjacent the crotch thereof, said opening having opposite portions produced by converging edges which intersect each other, a piece of flexible ma-

terial fitting said opening and having its edges secured to the edges providing said opening, said piece having holes providing vents therein, a second piece of flexible material having opposite edges in alinement with and secured by stitching to opposite edges of said first piece, said second piece having two other edges which span the tapered portion of said first piece and are secured thereto by elastic stitching, said second piece having holes in alinement with the holes of said first piece and forming

vents, the edges forming the vents of each of said pieces being bound by stitching which passes through and secures both of 15 said pieces together, substantially as described.

In testimony whereof I have signed my name to this specification in the presence of two subscribing witnesses.

LOUIS TOPKIS.
